PURIFICATION OF NAPHTHENIC ACIDS

Frederick J. Ewing, Pasadena, Calif., assignor to
Union Oil Company of California, Los Angeles,
Calif., a corporation of California

Application July 2, 1935, Serial No. 29,495

8 Claims. (Cl. 260—514)

This invention relates to a process for the purification of naphthenic acids.

Crude naphthenic acids, obtained from alkaline sludges arising during the refining of petroleum fractions, shale oil fractions, coal tar and its fractions or those obtained by synthesis (for instance by oxidation of liquid, gaseous or solid hydrocarbons) all contain various constituents which tend to detract from their commercial value. Therefore, in order to produce naphthenic acids of high market value, it is necessary to remove these impurities therefrom.

Processes are known which relate to the removal of phenols from naphthenic acids after both have been liberated simultaneously from the various alkaline residues arising in the refining of petroleum fractions. However, in these no provisions are made for the removal of the impurities hereinafter mentioned from the phenol-free naphthenic acids.

The impurities which are oftentimes associated with naphthenic acids and which impair their value are asphalt like substances such as carbonaceous materials, bitumens, asphalt; hydroxy-carboxylic acids or other hydroxy-acids, wax and wax-like bodies and various color-forming bodies of yet unknown composition and structure. It should be obvious that all of these impurities need not all be present in the impure naphthenic acids at any one time as the number and amounts thereof are usually in some manner related to the particular stock from which the naphthenic acids are produced and the manner of isolation thereof. In any event, no matter which one or ones of the particular impurities are present in the naphthenic acids, they will unfavorably influence their commercial desirability especially in regards to color, odor, viscosity or their use for the manufacture of driers, siccatives, cosmetics or the like.

The term "naphthenic acids" used herein is intended to be generic and not limited to any particular kind of naphthenic acids or to naphthenic acids derived from any particular crude material or by any specific methods of isolation from various media in which they are normally encountered.

I have discovered that naphthenic acids containing impurities such as the asphalt-like substances, exemplified by carbonaceous materials, bitumens and asphalts; hydroxy-acids, wax and wax-like bodies, color forming bodies and the like or mixtures of these impurities, may be separated therefrom by the use of certain diluent solvents in which the naphthenic acids are readily soluble but in which the impurities are substantially

insoluble. Hence, by commingling crude naphthenic acids with a suitable portion or suitable portions of a solvent in which the naphthenic acids are soluble but toward which the impurities show only a limited solubility, I am able to separate the various above enumerated impurities from the crude or impure naphthenic acids and obtain a product of desirable characteristics such as light color, bland odor, absence of cloudiness, high acid number etc.

The solvents which I may employ for the separation of the foregoing impurities from naphthenic acids include such materials as petroleum naphtha, petroleum ether (a light paraffinic petroleum distillate having a specific gravity between 0.685 and 0.650) natural gasoline, liquid aliphatic hydrocarbon such as liquid ethane, liquid ethylene, liquid propane, liquid propylene, liquid butane, liquid isobutane, pentane, hexane or mixtures of these hydrocarbons which may or may not include methane.

I prefer to use as a diluent solvent for the separation of the foregoing impurities from crude naphthenic acids, light hydrocarbons which are normally vaporous at ordinary temperatures and pressures. These hydrocarbons include methane, ethane, ethylene, propane, propylene, butane and isobutane or mixtures thereof. Excellent results are also obtainable when using a diluent solvent consisting substantially only of propane. This solvent is a liquid at a temperature of 72° F. when maintained under a pressure of about 125 lbs. It has a boiling point of approximately —40° F.

The liquefied normally gaseous hydrocarbons are preferable over ordinary low boiling petroleum distillates such as benzine, ligroin or the like because they are capable of separating substantial amounts of impurities from crude naphthenic acids, not removable therefrom with the above mentioned low boiling petroleum distillates. It is entirely possible to obtain a substantially pure naphthenic acid product by treating crude naphthenic acids with a liquefied normally gaseous hydrocarbon only, without further treatment, while in the use of a low boiling petroleum distillate sufficient amounts of impurities are carried over into the refined naphthenic acids to require a subsequent chemical treatment thereof for the purpose of removing the color giving bodies and other impurities which were not removed by the above mentioned petroleum distillates.

In the separation of the foregoing impurities from crude naphthenic acid the crude stock is commingled with one of the foregoing solvents and the naphthenic acids present in the crude

stock dissolve in the solvent while the impurities remain undissolved. This mixture may then be settled, filtered or centrifuged to separate the solvent solution of naphthenic acids from the undissolved impurities.

When I employ liquefied normally gaseous hydrocarbons, such as propane, for the separation of impurities from crude naphthenic acid, I find that the best separation occurs when I employ about 1 to 3 volumes of the liquefied normally gaseous hydrocarbon to one volume of the crude naphthenic acids. For example, when one volume of the crude naphthenic acids is commingled with two volumes of liquid propane under pressure and at a temperature of about 70° F., I find that the naphthenic acids are soluble in the liquid propane but the impurities such as the asphalt-like substances comprising carbonaceous materials, bitumen, asphalt; hydroxy acids and color bodies are substantially insoluble therein. If this mixture of crude naphthenic acids with liquid propane is settled, filtered or centrifuged, I am able to separate the major portion of the impurities from the naphthenic acids dissolved in the liquid propane.

As a means of further refining the acids after the initial separation of impurities with solvents, I may employ chemical reagents and I find that such a chemical treating step is much more effective and complete if carried out in the presence of the diluent which I employ for the initial separation of the impurities present in the crude naphthenic acids. For example, the crude naphthenic acids may be extracted with a liquefied normally gaseous hydrocarbon, such as propane, for the separation of a major portion of the impurities present, in the manner above described, whereupon the naphthenic acids dissolved in the liquefied normally gaseous hydrocarbon may be further purified by means of a chemical treatment. This treatment may comprise the use of reagents such as sulphuric acid, chloric acid, bromic acid, iodic acid, hydroiodic acid, nitric acid, chlorsulphonic acid, nitrosulphonic acid, phosphoric acid, decolorizing agents such as fuller's earth or diatomaceous earth, acid activated decolorizing earths such as "Filtrol" (fuller's earth activated with dilute sulphuric acid) or metallic halides such as aluminum chloride, zinc chloride or iron chloride. The result of such a chemical treat may be said to reside in further improving the odor and color of the naphthenic acids.

In some cases the crude naphthenic acids may not contain a sufficient quantity of impurities to obtain an initial separation thereof with the above-mentioned solvents, in which case it may only be necessary to employ the chemical treatment of the crude naphthenic acid stock in the presence of the solvent. For example, the crude naphthenic acid stock may be dissolved directly in one of the foregoing solvents, for example a liquefied normally gaseous hydrocarbon such as propane and directly treated with one or all of the foregoing reagents such as acid, clay or metallic halides or mixtures thereof. These reagents and their associated impurities may then be separated from the naphthenic acids dissolved in or diluted with the solvent by such means as settling, centrifuging or filtering.

In the foregoing description I have described the use of diluents at ordinary temperature for the separation of carbonaceous material, bitumens, asphalts, hydroxy-acids and color bodies from crude naphthenic acids. In some cases I

find that these impurities are more effectively separated from the crude naphthenic acids by the use of the foregoing solvents at low temperatures. For example, in some cases I may extract 5 the crude naphthenic acid with one of these solvents within the temperature range of +10° F. to -40° F. and at these lowered temperatures obtain a more complete separation of the impurities from the crude naphthenic acids.

In case the crude naphthenic acids are extracted with a liquefied normally gaseous hydrocarbon, the lowered temperature may be obtained by vaporizing a portion thereof under reduced pressure from the mixture. For example, the 10 crude naphthenic acids may be diluted with 3 to 5 volumes of a liquefied normally gaseous hydrocarbon, such as propane, and a portion of the propane may be vaporized under reduced pressure to chill the mixture. The propane solution of 15 naphthenic acids may thus be separated from the undissolved impurities by settling, filtration or centrifuging. In case excessive amounts of the liquefied normally gaseous hydrocarbon have been removed by vaporizing, I may add supplementary amounts of these hydrocarbons preferably pre-cooled to the desired temperature.

Furthermore, in some cases I find that the chemical treatment of the crude naphthenic acids may be effectively carried out at low temperatures. For example, the naphthenic acids 20 diluted with one of the foregoing liquefied normally gaseous hydrocarbon solvents may be treated with such materials as sulphuric acid, hydrochloric acid, nitric acid, or any of the other 25 acids enumerated above, or metallic halides at temperatures ranging from +10° F. to -40° F. for the separation of the impurities present therein. Where chemical treatment is employed, the saturated aliphatic diluents such as propane 30 should be used in preference to unsaturated aliphatics such as ethylene, as the latter tend to react with various chemicals such as sulphuric acid to form polymerized products which would hinder or counteract the purification of the dissolved naphthenic acids.

In the separation of the asphalt-like substances (carbonaceous material, bitumen, and asphalt) hydroxy-acids and color bodies from crude naphthenic acids, it may also be found 35 advantageous to employ stage separation. For example, the crude naphthenic acids may be commingled at about 70-80° F. with a liquefied normally gaseous hydrocarbon and the hydrocarbon solution of naphthenic acids may then be separated from the undissolved impurities. This 40 solution of naphthenic acids in the liquefied normally gaseous hydrocarbon may then be cooled in successive stages for the separation of a further quantity of impurities and the impurities 45 separated at the lowered temperatures may then be removed from the cooled solution of naphthenic acids dissolved in the liquefied normally gaseous hydrocarbon.

In addition to the above-mentioned impurities, 50 crude naphthenic acids may also contain solid, wax-like acids which tend, under normal conditions of temperature to crystallize out of the purified naphthenic acids unless steps are taken for their removal. The presence of these solid acids 55 tends to raise the cloud point and pour point of the naphthenic acids. These wax-like acids are probably high molecular weight aliphatic acids, although I do not wish to be limited by any such theory. Their removal from naphthenic acids 60 by chilling and filtering is tedious and wasteful 65

due to the high viscosity and slimy quality of the naphthenic acids and waxy material at low temperatures. However, these solid acids may be readily removed from naphthenic acids containing them by dissolving the crude stock in a solvent such as a liquefied normally gaseous hydrocarbon and cooling the solution. They may then be removed in an expedient manner from the solvent solution of the naphthenic acids by filtering, settling or centrifuging.

In want of a better term to designate these wax-like solid acids, I have chosen to call them "wax" although strictly speaking they are not analogous to or comparable with the solid paraffin hydrocarbons usually designated by that name. I have also discovered that naphthenic acids may be separated from crude naphthenic acids containing asphalt-like impurities as carbonaceous material, asphalt, bitumen; hydroxy-acids or color bodies, by leaching or extracting the crude stock at low temperature with light hydrocarbon solvents such as naphtha, casinghead gasoline, liquid propane, liquid ethane, liquid butane or mixtures thereof or mixtures of similar hydrocarbons. For example, I may commingle the crude naphthenic acid stock with liquid propane at a temperature ranging from 0° F. to -40° F. and at the lowered temperature the naphthenic acids dissolve in the solvent while the impurities remain undissolved. The solvent solution of naphthenic acids may then be separated from the undissolved impurities by filtering, settling or centrifuging, or by other conventional means.

It is therefore an object of this invention to separate naphthenic acids from crude naphthenic acid stock containing asphalt-like impurities such as carbonaceous materials, bitumens and asphalt; hydroxy-acids, color bodies or waxes or mixtures of these impurities, and in doing so obtain a naphthenic acid product possessing improved characteristics in regard to odor, color, viscosity and pour point.

It is another object of this invention to separate impurities contained in crude naphthenic acids by means of solvents in which the naphthenic acids are soluble and in which the impurities are substantially insoluble.

It is another object of this invention to extract crude naphthenic acids containing impurities with solvents in which the naphthenic acids are substantially soluble and in which the impurities are substantially insoluble, separate the solvent solution of naphthenic acids from the bulk of the insoluble impurities and further refine the solvent solution of naphthenic acids with reagents such as mineral acids, decolorizing clay or metallic halides or with mixtures of these reagents.

Other objects of my invention will be apparent from the description covering the various features of my process.

The process of this invention may be more fully understood by reference to the accompanying figure which represents a preferred embodiment thereof. Referring to the drawing, crude naphthenic acid stock in tank 1 is withdrawn through valve 2 and passed by means of pump 3 through line 4 where it is commingled with liquid propane containing a small amount of dissolved naphthenic acids. The mixture in line 4 then passes to mixer or agitator 5 where thorough mixing of the crude naphthenic acid and liquid propane takes place. The mixture in agitator 5 then passes via line 6 to decanter 7 where it is settled. The insoluble impurities in decanter 7 settle to

the bottom thereof and are withdrawn through valve 8 and line 9 to agitator or mixing coil 10 where the insoluble impurities are commingled with liquid propane withdrawn from tank 15 through valve 16, pump 17 and line 18. After thorough agitation of the mixture in agitating coil 10 it passes into separator 11 where the insoluble impurities such as carbonaceous material, asphalt, bitumens (asphalt-like substances), hydroxy-acids or color bodies or mixtures of these impurities settle to the bottom of the decanter and are withdrawn through valve 12 and line 13. The overflow from decanter 11 consisting of liquid propane and a small quantity of dissolved naphthenic acid is withdrawn through line 14 and returned to line 4 as explained above.

The overflow from decanter 7 consisting of naphthenic acids dissolved in the liquid propane is withdrawn through line 19, provided with pump 20.

In case the naphthenic acids contain impurities which are not eliminated by the preceding treatment, it may be further refined for the removal of the remainder of the impurities. For example, the overflow from decanter 7 which is withdrawn through line 19 may be passed by pump 20 through line 24 to mixing coil 58 where it is mixed with a refining agent such as sulphuric acid, nitric acid, phosphoric acid, chloric acid, iodic acid, bromic acid, stored in tank 21 and withdrawn through valve 22, pump 23 and line 61 into mixing coil 58. The refining agent introduced into mixing coil 58 may also comprise such materials as aluminum chloride, zinc chloride, iron chloride or decolorizing clay such as fuller's earth or diatomaceous earth, "Filtrol" or the like.

The mixture in mixing coil 58 comprising the refining agent commingled with the propane solution of naphthenic acid, then passes to decanter 25 where the refining agent and its associated impurities settle to the bottom of the decanter and are removed through valve 26 and line 27. The chemically treated naphthenic acids dissolved in the liquid propane and free from the refining agent and associated impurities are withdrawn from the top of the decanter 25 through valve 28 and line 29.

In case the crude naphthenic acid contains wax or wax-like bodies the treatment which has been so far described, with respect to the figure, will not completely remove these waxes or wax-like bodies. For the removal of the wax, the propane solution of naphthenic acids in line 29 passes by means of pump 30, line 33 and valves 59 and 69 into chiller 34 where the temperature of the propane solution may be reduced to a sufficient degree to cause the wax present in the propane solution to precipitate. The cooling of the propane solution in chiller 34 may be produced by means of cooling coils inserted in chiller 34 (not indicated in the drawing) but is most conveniently produced by allowing a portion of the propane to vaporize under reduced pressure from chiller 34 by opening valve 35. The degree of cooling necessary in chiller 34 will depend upon the stock being treated and any temperature from +10° F. to -40° F. may be attained by merely opening valve 35 and allowing the propane to evaporate from the solution under reduced pressure. If desired, additional liquid propane may be introduced into chiller 34 to supply the necessary refrigeration and the proper dilution of the chilled mass in chiller 34 for efficient separation of the wax from the propane solution of naphthenic

acid. The introduction of this "make up" propane is more or less optional and the means for doing this have not been indicated in the drawing.

The propane vapors removed from chiller 34 through valve 35 pass through line 36 to compressor 37 where they are compressed and then pass via line 38 to cooler or condenser 60 where they are liquefied and thence to storage tank 15, via line 62 and valve 63.

The cooled mass in chiller 34 is withdrawn through valve 64 into line 40 and sent by means of pump 41 and line 42 through filter 43 where the precipitated wax is removed from the propane solution of naphthenic acid. The wax is withdrawn from filter 43 through line 44 and valve 65 and the propane solution of dewaxed naphthenic acids passes from the filter through line 45, valve 46, line 47 to pump 48 which forces this solution through line 49 into evaporator 50 where the liquid propane is removed from the naphthenic acid. Evaporator 50 is supplied with heating coils 51 which vaporize the propane. The propane vapors are withdrawn from evaporator 50 through valve 55 and pass via line 56 to compressor 57 where the vapors are compressed and pass via line 38 to cooler 60 where they are liquefied and are returned to storage tank 15. The wax recovered from filter 43 is relatively free from asphalt-like bodies as these impurities have been eliminated by the prior solvent treatment and/or chemical treatment.

The purified naphthenic acids are withdrawn from evaporator 50 through valve 52 and line 53 into refined naphthenic storage 54.

In some cases I find that the wax may be more readily separated from the naphthenic acids by the use of filter aid. The filter aid may be introduced into the propane solution of naphthenic acids containing wax by means of line 31 and valve 32 into line 33. After the solution of naphthenic acids containing the filter aid in chiller 34 has been cooled sufficiently to precipitate the wax, the chilled mass in chiller 34 is then passed through filter 43 for removal of the wax and filter aid from the propane solution of naphthenic acid. As filter aids I may use keiselguhr, sawdust, diatomaceous earth, fuller's earth or clay.

As has been explained above, I find that many naphthenic acid stocks contain wax which separates from the acid in solid form at ordinary temperature or slightly reduced temperature after certain of the impurities present in the crude naphthenic acid have been removed. Thus, if the solvent treatment and/or chemical treatment has removed substantially all of the impurities in the crude naphthenic acids other than the wax, the latter will separate from the naphthenic acid without any substantial reduction in temperature.

Where the solvent treatment and/or chemical treatment has removed sufficient of the impurities to permit separation or precipitation of the wax from the naphthenic acid at ordinary temperature, chiller 34 may be eliminated or employed only to produce a slight reduction in the temperature of the solution to cause separation of the wax from the naphthenic acids.

Furthermore, as has been explained above, my process may be operated in such a manner that the wax may be removed simultaneously with any or all of the other impurities mentioned herein. In such instances the crude naphthenic acid stock in tank 1 is commingled with liquid

propane from tank 15 at ordinary temperatures while the temperature in mixing coils 5 and 10 and in decanters 7 and 11 is maintained at sufficiently low temperature (for instance between

5 $+10^{\circ}$ F. and -40° F.) to cause the wax to be separated together with the other impurities present in the crude naphthenic acids. These low temperatures may be created by surrounding mixing coils 5 and 10 with cooling jackets 10 through which cooled brine is allowed to circulate or into which liquefied propane may be introduced and allowed to evaporate. I may also provide cooling of the mixture of crude naphthenic acids and propane (or similar liquefied 15 normally gaseous hydrocarbon) by allowing a portion of the propane present in decanter 7 to vaporize, the vapors escaping through line 67 provided with valve 66. The vapors in line 67 are passed into the suction side of compressor 68 20 which compresses them and causes their introduction into line 38 where they are commingled with the propane vapors already present therein and pass into cooler 60 and subsequently into propane storage 15. The wax will then be eliminated along with the other impurities from decanter 11 through line 13 provided with valve 12. If desired, the wax which is acidic in nature may be separated from the asphaltic materials precipitated therewith by extraction with an alkaline 30 material such as sodium hydroxide which will selectively remove the wax (in the form of salts) from the asphaltic materials. The acids contained in the wax may be liberated from these salts by means of an inorganic acid.

35 As a modification of the wax removal process above described, I may commingle the crude naphthenic acids with a solvent at a temperature sufficiently low to prevent solution of the wax and thus simultaneously remove the wax and 40 other impurities which are insoluble in the solvent employed. For example, I may cool the liquid propane or other solvent in lines 14 and/or 18 to a suitable low temperature ($+10^{\circ}$ F. to -40° F.) before commingling it with the crude 45 naphthenic acids withdrawn from tank 1. In such instance, the decantate in line 19 will be substantially wax-free as the wax will have been eliminated from the bottom of decanter 11 through valve 12 and line 13. The naphthenic 50 acids dissolved in the solvent present in line 19 may be further purified with chemical reagents in the remaining stages of the process. The wax removal after the chemical treatment or treatment with the adsorbent materials or after a 55 combination of these two treatments, may be eliminated if desired, as most of the wax has been removed in decanter 11.

In case it is desirable to carry out the chemical treatment at a reduced temperature (not sufficiently low to cause wax separation) I may vaporize only sufficient propane from decanter 7 to create such a temperature without causing wax separation, or I may altogether eliminate the vaporization in decanter 7 and provide suitable heat exchangers in line 19 (not indicated in the drawing).

It has been found preferable in most instances to subject the dissolved naphthenic acids to a treatment with an adsorbent material subsequent to the chemical treatment thereof, previously described. Referring to the drawing, this adsorbent treatment may be carried out by providing an adsorbent storage tank 70 capable of discharging suitable amounts of the adsorbent via line 72, 70 screw conveyor 82, line 83 and valve 71 into the

solution of naphthenic acids in the solvent leaving decanter 25 via line 29, valve 28; pump 30 and line 13. This may be accomplished by closing valve 69 and opening valve 81 (which is closed when the adsorbent treatment is not being employed). The mixture of naphthenic acids, solvent and adsorbent is then introduced via line 14 into agitator 75 provided with suitable agitating means 72. The adsorbent containing the impurities removed thereby as well as residual amounts of the chemicals remaining in the naphthenic acids after chemical treatment, are removed from the bottom of agitator 75 via line 80 and valve 79. Small amounts of the solvent adhering to the spent adsorbent may be recovered by heating it in a heating vessel (not shown) and passing the vapors so liberated to one of the vapor gathering lines 57, 38, 36 or 56.

The decantate from agitator 75 (after the agitation has stopped) passes via line 17 and valve 78 into chiller 34 whereupon it may be chilled for dewaxing purposes in the manner previously described. If small amounts of adsorbent are carried over into chiller 34 they will serve as dewaxing aids during the dewaxing operations. Suitable settling means (not shown) in which any adsorbent carried over from agitator 75 may be removed, may be provided in line 17, if so desired. Valve 78 will remain closed in those operations in which the adsorbent treatment after chemical treatment is not being used. The adsorbent will tend to act as a coking agent in those instances where sludge forming acids such as concentrated sulphuric acid are used. When used in sufficient amounts, it will operate in such a manner as to decolorize and deodorize the naphthenic acids and in any event will supplement the action of the chemical reagent.

The equipment used in the process of my invention is preferably constructed out of material showing little or no corrosion in the presence of naphthenic acids. Acid resistant steel or steel alloys and aluminum lined equipment or other non-corrosive steels or alloys recently put on the market have been found to be suitable. Evaporator 59 and heating coil 51 should preferably be constructed out of acid resistant materials in view of the increased temperature prevailing therein. I have, however, found that where propane or similar liquefied normally gaseous hydrocarbons are used in my process that the corrosion problem has been materially reduced and that the conventional iron or steel equipment may be employed.

It should be obvious to anyone that in view of the use of liquid normally gaseous diluents, the system will have to operate under pressure and the equipment used in my process will have to be constructed in cases where diluents such as propane are used to withstand pressures as high as 150 to 200 pounds or greater. The equipment used for heating or cooling should preferably be insulated against temperature loss.

The removal of the naphthenic acids from the diluent solvent may be accomplished by means other than heating, although the latter appears to be the most economical. For instance, I may extract the solution of the purified naphthenic acids with an alkaline reagent such as sodium hydroxide, potassium hydroxide, calcium hydroxide or the like, and separate the naphthenic acid soaps so produced from the solvent. These soaps may then be extracted, if desired, with suitable amounts of solvents such as naphtha, petroleum ether, gasoline or the like, to remove any heavy

hydrocarbon fractions carried over into the soaps and the free naphthenic acids may then be obtained by commingling the soaps with an inorganic acid, preferably sulphuric acid.

5 I may also finally distill the naphthenic acids after completion of the other purifying steps to produce a finished product which is light in color and does not darken on standing.

Crude naphthenic acids contain impurities 10 which are unstable and tend to darken when exposed to light. When such crude naphthenic acids are distilled, these unstable bodies are carried over in the distillate fractions and due to their instability soon darken the distillate. If, however, the crude naphthenic acids are first extracted with a liquefied normally gaseous hydrocarbon, such as liquid propane, and the propane soluble portion recovered from the crude naphthenic acid is distilled, preferably by vacuum distillation, the distillates so produced are free from these unstable bodies and have a very pronounced color stability. The impurities which cause the darkening of the distillates are substantially insoluble in liquefied normally gaseous hydrocarbons, such as ethane, propane, butane and mixtures thereof. Therefore, by first extracting the crude naphthenic acids with a liquefied normally gaseous hydrocarbon and then distilling the portion which is soluble in the liquefied normally gaseous hydrocarbon, distillate fractions are recovered which have a high color stability.

Furthermore, I may also extract the crude naphthenic acids with a liquefied normally gaseous hydrocarbon, treat the portion which is soluble in the liquefied normally gaseous hydrocarbon with mineral acids such as sulphuric acid, hydrochloric acid, chloric acid, bromic acid, iodic acid, hydroiodic acid, phosphoric acid, chlor-sulphonic acid, nitrosulphonic acid either in the presence or absence of the liquefied normally gaseous hydrocarbon and then distill the extracted and acid treated naphthenic acids into fractions. Furthermore, I may extract the crude naphthenic acids with a liquefied normally gaseous hydrocarbon according to the methods set forth above, treat the extracted acids with any of the above mentioned mineral acids, treat the acid treated naphthenic acids with decolorizing clay (such as fuller's earth) and then distill the acid and clay treated naphthenic acids into fractions or I may omit the mineral acid treatment of the extracted acids and treat the liquefied normally gaseous hydrocarbon extract of the crude naphthenic acids with clay alone and then distill the clay treated naphthenic acids into fractions. The clay treatment may be carried out on the naphthenic acid commingled or dissolved in the liquefied normally gaseous hydrocarbon or I may remove the liquefied normally gaseous hydrocarbon from the extract prior to the clay treatment. By the term "extract" I mean those fractions contained in the crude naphthenic acid which are soluble in the liquefied normally gaseous hydrocarbon.

It is therefore an object of the present invention to commingle crude naphthenic acids with a liquefied normally gaseous hydrocarbon solvent to separate naphthenic acids dissolved in the liquefied normally gaseous hydrocarbon solvent from impurities insoluble in the light hydrocarbon solvent, recover the naphthenic acids dissolved in the light liquefied normally gaseous hydrocarbon solvent as an extract and distill this extract into fractions. The distillation is for the purpose of separating the naphthenic acids into

distillates of substantially pure form from the remaining impurities therein which are left as bottoms or residues in the still. Furthermore, it is an object of this invention to acid and/or clay treat the liquefied normally gaseous extract obtained from the crude naphthenic acids prior to the distillation.

The general effect of the purification process herein described is to transform crude naphthenic acids into a product having a light color, a bland odor, a high acid number (number of milligrams of KOH necessary to neutralize 1 gram of substance) as well as a substantial freedom from wax-like, solid acids, asphalt-like substances and other undesirable impurities whose exact composition has not yet been determined.

It will be noted from the above description that the process may be operated in such a manner as to obtain two separations of wax from the naphthenic acid stock. For example a portion of the wax may be removed by separator 11 during the solvent treatment in which other impurities are also removed from the naphthenic acid stock and a further quantity of wax may be removed from the partially purified stock by filter 43. By chilling the solvent solution of naphthenic acids discharged from decanter 7 through lines 19, 29 and 33 into chiller 34, a further quantity of wax precipitates which may be removed by filter 43 from the naphthenic acids dissolved in the solvent. Furthermore, if the overflow in line 19 is chemically treated the remaining wax usually precipitates from the solution at ordinary temperature or at slightly reduced temperature and this wax may be removed by filter 43. The chemical treatment removes certain bodies present which tend to hold the wax in solution. Therefore by removing the impurities from the solution of naphthenic acids recovered in line 19 by chemical treatment prior to the dewaxing step in filter 43, a more complete separation of wax may be obtained from the naphthenic acid. The degree of cooling of the chemically treated solution of naphthenic acids entering chiller 34 varies with the stock. In most instances only slight or moderate chilling is necessary to cause separation of the wax from the chemically treated solution; however I find that in some instances it is desirable to lower the temperature of the chemically treated stock in chiller 34 from 0° F. to -40° F. to obtain substantially complete precipitation of the wax present.

The description of the drawing as well as other specific descriptions occurring herein, are not intended as limitations upon my process. As to the scope thereof, reference is made to the appended claims.

I claim:

1. A method for purifying crude naphthenic acids containing wax which comprises commin-

gling said acids with a low boiling hydrocarbon diluent adapted to dissolve the naphthenic acids and the wax at elevated temperature and to selectively precipitate the wax upon cooling, cooling the solution so obtained to precipitate wax, and separating the precipitated wax from the naphthenic acids dissolved in the said diluent.

2. A method as defined in claim 1 wherein the diluent is a liquefied normally gaseous hydrocarbon.

3. A method as defined in claim 1 wherein the diluent used is a liquefied normally gaseous hydrocarbon and the chilling of the solution of naphthenic acids in said liquefied normally gaseous hydrocarbon is produced by evaporating a portion thereof.

4. A method of purifying crude naphthenic acids which comprises commingling said acids with a light petroleum hydrocarbon diluent to dissolve the acids and wax and precipitate the asphalt-like bodies, removing the asphalt-like bodies from the solution of naphthenic acids and wax, chilling said solution to precipitate wax and removing the wax from the naphthenic acids and light petroleum hydrocarbon diluent.

5. A method of purifying crude naphthenic acids which comprises commingling said acids with a liquefied normally gaseous hydrocarbon to dissolve the acids and wax and precipitate the asphalt-like bodies, removing the asphalt-like bodies from the solution of naphthenic acids and wax, chilling said solution to precipitate wax and removing the wax from the naphthenic acids and liquefied normally gaseous hydrocarbon diluent.

6. A method of purifying crude naphthenic acids which comprises commingling said acids with a liquefied normally gaseous hydrocarbon diluent to dissolve the acids and wax and precipitate the asphalt-like bodies, removing the asphalt-like bodies from the solution of naphthenic acids and wax, chilling said solution to precipitate wax by evaporating a portion of the liquefied normally gaseous hydrocarbon and removing the precipitated wax from the naphthenic acids and remaining liquefied normally gaseous hydrocarbon diluent.

7. A method of purifying crude naphthenic acids which comprises diluting said acids with a liquid hydrocarbon diluent having a substantially lower boiling point than that of said acids and contacting the diluted acids with clay.

8. A method of purifying crude naphthenic acids which comprises contacting said acids with clay in the presence of a hydrocarbon diluent of substantially lower boiling point than the naphthenic acids being treated, separating the treated acids from the clay and separating the clay treated acids into fractions by distillation.

FREDERICK J. EWING.
